UNITED STATES PATENT OFFICE.

MAX SCHNEFEL, OF NEWARK, NEW JERSEY.

DESIGN FOR A BUTTONHOOK.

Application filed August 15, 1922. Serial No. 3,388. Term of patent 7 years.

To all whom it may concern:

Be it known that I, MAX SCHNEFEL, a citizen of the United States, residing at Newark, in the county of Essex and State of New Jersey, have invented a new, original, and ornamental Design for a Buttonhook or Similar Article, of which the following is a specification, reference being had to the accompanying drawing, forming a part thereof.

The invention is clearly illustrated in said accompanying drawing, which shows my

new, original, and ornamental design for the button hook, or similar article; and in which, Figure 1 is a side view; Figure 2 an edge view; and Figure 3 a horizontal sectional representation of the button hook.

I claim:—

The ornamental design for a button hook, or similar article, as shown.

MAX SCHNEFEL.
